UNITED STATES PATENT OFFICE.

JOHN F. THOMPSON, OF AVA, MISSOURI, ASSIGNOR OF ONE-HALF TO
ALEXANDER H. BUCHANAN, OF AVA, MISSOURI.

BEEHIVE.

SPECIFICATION forming part of Letters Patent No. 723,424, dated March 24, 1903.

Application filed September 30, 1901. Serial No. 77,093. (No model.)

To all whom it may concern:

Be it known that I, JOHN F. THOMPSON, a citizen of the United States, residing at Ava, in the county of Douglas and State of Missouri, have invented certain new and useful Improvements in Beehives, of which the following is a specification.

This invention relates to beehives, and has special reference to a simple and practical construction of hive comprising means for thoroughly protecting the bees against moths, while at the same time insuring their working under the best possible conditions.

A further object of the invention is to construct the hive in a simple and inexpensive manner, with the parts thereof so arranged as to be readily accessible. In this connection the invention contemplates improved means for opening up the hive in such a manner as to permit of ready access to both the sections or frames in the super and in the brood-chamber.

With these and many other objects in view, which will more readily appear to those familiar with the art as the nature of the invention is better understood, the same consists in the novel construction, combination, and arrangement of parts hereinafter more fully described, illustrated, and claimed.

In the accompanying drawings, Figure 1 is a perspective view of a hive constructed in accordance with the present invention and showing the top cover and side door thrown open. Fig. 2 is a vertical longitudinal sectional view of the hive. Fig. 3 is a vertical cross-sectional view thereof. Fig. 4 is a plan view with the top cover and upper side door removed and also the several holding-boxes for the honey sections or frames removed from the super. Fig. 5 is a detail in perspective of one of the open holding-boxes which are arranged in the super for the reception of the upper honeycomb-frames.

Like numerals of reference designate corresponding parts in the several figures of the drawings.

In carrying out the invention the hive-body 1 essentially consists of a rectangular casing supported upon suitable supporting legs or standards 2 and provided with a V-shaped bottom 3, consisting of downwardly-converg-

ent bottom boards 4. The said V-shaped bottom 3 of the hive body or casing is provided in one side contiguous to its apex with a plurality of bee-entrance openings 5, corresponding in number to the plurality of separate compartments 6 of the lower brood-chamber 7, each of the bee-entrance openings 5 being in communication with one of the brood-chamber compartments 6 at the bottom of 60 such compartment. The main body portion of the hive body or casing 1 incloses the brood-chamber 7, and within this chamber are fitted a series of vertical regularly-spaced partitions or walls 8, which divide the brood-chamber into a number of compartments 6, which compartments receive therein a series of brood or comb frames 9.

The brood or comb frames 9 are of substantially the ordinary form; but in the present 70 invention the same are suspended within the separate compartments 6 from the top thereof and are arranged side by side in close relation. To permit of the passage of the bees into and out of the said series of frames 9 in 75 each brood-chamber compartment 6, the frames are provided in the contiguous edges of their upper and lower sides with matching notches 10, which necessarily form openings through which the bees may pass, those at 80 the bottom of the frames 9 permitting the bees to enter the frames and those at the top of the frames permitting the bees to pass into the super 11 at the top of the hive body or casing.

The upper side pieces of the brood or comb 85 frames 9 are extended at their ends to form supporting-lips 12, detachably resting upon the shoulders 13, provided at the upper side edges of the brood-chamber 7.

The super 11 is preferably formed by an 90 open extension of the hive body or casing above the plane of the shoulders 13. The open front side of the super is adapted to be covered and uncovered by the side door 14, hinged at its lower edge, as at 15, to the hive-body, and when closed having its upper edge held in and engaged by the flanged top cover 16, hinged at one edge, as at 17, to the back extension forming a part of the super 11.

The super 11 accommodates therein a plurality of individual holding-boxes 18, arranged removably and side by side on top of

the frames 9 within the brood-chamber. The said boxes 18 are open at the top and bottom and individually accommodate a series of honey-sections 19, fitting closely side by side 5 and provided at the side edges of their bottom pieces 20 with matching notches 21, which provide openings corresponding with those at the top of the brood-frames 9, so that the bees may readily pass from said brood-frames into 10 the sections 19 within the super.

By reason of the partitioned construction described it is observed that the hive-body is divided into a plurality of compartments which accommodate separate swarms of bees.

15 By thus swarming the bees heat is generated which promotes their propagation, and consequently increases the supply of honey.

From the foregoing it is thought that the construction and many advantages of the 20 herein-described hive will be readily apparent without further description, and it will be understood that various changes in the form, proportion, and minor details of construction may be resorted to without departing from 25 the spirit or sacrificing any of the advantages of the invention.

Having thus described the invention, what I claim as new, and desire to secure by Letters Patent, is—

In a beehive, the hive-body having a bottom brood-chamber partitioned to form a plurality of compartments or rooms, and above said brood-chamber being provided with a super open at the top and one side, a series of brood-frames removably suspended within each compartment of the brood-chamber and provided with matching openings at top and bottom, a series of holding-boxes open at top and bottom and arranged within the super on top of said brood-frames, a plurality of honey- 35 sections arranged within each of said boxes and provided at the bottom with openings registering with the top openings of the brood-frames, a side door for the open side of the super, and a top cover for the open top thereof. 40

45 In testimony whereof I affix my signature in presence of two witnesses.

JOHN F. THOMPSON.
